UNITED STATES PATENT OFFICE

2,601,921

DEVICE FOR GAUGING AND SORTING ARTICLES

Theodore A. Jagen, Livingston, N. J., assignor to General Motors Corporation, Detroit, Mich., a corporation of Delaware

Application June 30, 1948, Serial No. 36,242

12 Claims. (Cl. 209—88)

1

This invention relates to the gauging of articles and comprises all of the features of novelty herein disclosed. An object of the invention is to provide improved apparatus for gauging articles for length and separating articles of unacceptable length from the others. Another object is to provide apparatus for extremely fast gauging as by the use of a pair of gauges to which the articles are successively presented by a rapidly oscillating transfer member. Another object is to provide improved apparatus for control of gauging as by the use of electronic switches having a control wire actuated by a very minute current which flows without arcing when a movable gauging finger actuated by an article of unacceptable size causes the control wire to be grounded.

To these ends and also to improve generally upon devices of this character, the invention consists in the various matters hereinafter described and claimed.

In the drawings

Fig. 1 is a front elevation, some parts which are left-handed duplicates of those at the right being removed.

Fig. 2 is a plan view partly in section, the two upper arms being broken away and some left-handed duplicates being removed.

Fig. 3 is a sectional view of an adjustable electric contact.

Fig. 4 is a side view with the gauging arms removed.

Fig. 5 is a plan view of the upper left hand arm.

Fig. 6 is a front view of a portion of the machine.

Fig. 7 is a rear view with the transfer arm in section.

Fig. 8 is an electric diagram.

Fig. 9 is a mechanical diagram in plan.

Fig. 10 is a diagram in front view.

Fig. 11 is a perspective view of a body viewed from the rear and right.

Referring first to diagrammatic Figs. 9 and 10 for an outline of important functions and parts, elongated rollers R are fed endwise in a stream over a platform 2 and successively impinge against a stop 4. A depending rib 6 on a long oscillating transfer arm 8 pushes each roller laterally, the foremost roller going to one side and the next roller being pushed to the other side. As a roller is pushed sidewise in either direction, it is gauged for length between the stop surface 4 and a gauging finger on a spring-compressed pivoted arm 10 which carries electric contacts on each side, one contact engaging a fixed

2

or undersize contact 12 when the rollers are too short and the other contact engaging an oversize contact 13 on a spring pressed pivoted arm 14 when the rollers are too long. In the gauging position the roller is pressed against the slanting edge of a pivoted pressure arm 16 which lines up the roller for gauging. If the roller is of acceptable length, no electric contact is completed and upon the next swing of the transfer arm to the same side, another roller is urged against the gauged roller and pushes it laterally over the upper edge of a closed trap door 18 for conduction to a receptacle.

Whenever one of the electric contacts is completed at either side of the platform, a pull solenoid 20 is energized to swing the trap door open thereby discharging the unacceptable undersize or oversize roller between the platform and the trap door. A single spring 22 connecting the trap doors returns each door to closed position when either solenoid is de-energized. Each of the various arms is pivoted at one end on reed springs to eliminate lost motion. The transfer arm 8 is swung in one direction by a solenoid 24 and is returned by a coil spring 26, its rapid oscillation being limited by stop screws 28. The electrical connections have electronic cycle control as will be later described.

Referring to the constructional details in Figs. 1, 2, 4, 6 and 11, the rollers to be gauged are urged endwise at high speed through a feed tube 30 which is clamped by a screw in a square opening in a clamping block 32, the latter having a vertical slotted leg 34 adjustably secured by screws on the front of a skeletonized body 36. At the front and rear of the body, lugs 38 and screws secure it to a base plate 40. Each side of the body has a pair of lugs 42 for a pivot pin 44 on which the trap door 18 is hinged. Each trap door is connected by a leaf spring 46 to a pin 47 on the plunger of one of the solenoids 20. The pins 47 project rearwardly beyond the body and are connected by the spring 22. Each solenoid is fastened to an angle bracket 49 on the base plate. The body 36 has a central partition 48 with projecting cheeks 50 having edges at an angle and the trap door is of similar angular shape to fit against those edges when closed. The hardened upper edge of the door terminates on a level with the platform 2 which is faced with hardened material. The platform has a depending tongue secured in a groove of the body. The rear of the body has spaced horizontal guiding rails 52 for a slide 54 which is adjustable lengthwise by a screw 56 journaled in a plate

58 attached to the rails 52. The slide has a depending tongue fitting between the rails and is clamped in adjusted position by a bottom plate 60 and a screw. A finger 62 projects forwardly over the platform from the slide and its forward end is hardened to form the end stop or abutment for the ends of the rollers.

As the rollers side out of the feed tube 39 towards the stop, they pass under a top guide 64 fastened to a rearwardly projecting lug on the block 32. The bottom of the guide has a V-groove enclosing the rollers. A plate 66 is fastened to the transfer arm 8 and carries the depending rib 6 which pushes the rollers laterally. Oscillation of the arm is limited by a forward projection operating between the stop screw 28 adjustably carried at the top of two standards 68 fastened on the front of the body 36. The transfer arm is of angular cross section made up of deep vertical plates welded to a narrow horizontal web and is hinged at its distant rear end by crossing leaf springs, two springs 70 extending lengthwise above and below a single cross spring 72. One end of each spring is secured to the arm and one end to a standard 74 on the base plate 40. The solenoid 24 (Fig. 7) is secured to an angle bracket 76 on the base and its plunger is connected by a leaf spring 78 to the transfer arm. A horizontal web on the transfer arm is tapped to receive a screw 80 connected by a coil spring 26 to an adjusting screw 84 in a standard 86. Thus the transfer arm is oscillated very rapidly through a short stroke.

The gauging arms are duplicated at each side of the machine. Fastened to the underside of each arm is a gauging finger 88 with a bent gauging tip opposed to the stop finger 62 and the distance between these surfaces is the length which is gauged. When a roller is pushed sideways by the rib 6, it is lined up in gauging position by the inclined lower edge of a bent locating finger 90 secured to the end of a slide 92 adjustably secured to the end of the angular pressure arm 16. The vertical portion of this arm is pivoted by vertical leaf springs 94 to the outer surface of a bracket 96 whose base 98 is slidably adjustable on the base plate by a screw 99. The weight of the arm 16 urges it downwardly to a limiting position provided by an adjusting stop screw 100.

Each gauging arm 10 is of insulating material and is pivoted by a leaf spring 102 to a side face on the bracket 96. A countersunk opening in the arm receives a circular flanged insert 104 having electric contacts on opposite sides. The arm is urged towards the fixed contact 12 by a coil spring 106. Each undersize contact 12 and each oversize contact 13 (Fig. 3) is carried by the enlarged end 108 of a screw 110 which is threaded in a sleeve 112 externally threaded in the split end of an arm having a clamping screw to hold the screws from turning after adjustment. The internal and external threads are of different pitch to provide a fine adjustment. The undersize contact arm 114 is rigidly fixed to the bracket 96. Extending forwardly at right angles from the arm 114 on its under side is an arm 116 provided with a pair of upright lugs 118 and 120 between which the oversize contact arm 14 has a limited movement. A coil spring 122 housed in the lug 120 urges the arm 14 towards an adjustable stop screw 124 in the lug 118. Each arm 14 is pivoted by a leaf spring 126 to the bracket 96.

Each bracket thus supports the four arms 10, 75

14, 16 and 114 and its adjustment by the screw 99 moves the arms towards or from the center as to set up for different work diameters. To adjust for length, the slide 54 is moved to locate the stop finger 62 at the correct distance from the gauging finger 88. Each gauging finger has a tapering surface to guide each roller to the actual gauging surface which extends straight across and parallel with the stop surface on the stop finger 62. The roller is lined up in this gauging position by the inclined edge of the locating finger 90. The differential screw adjustments at 112 for the fixed contact 12 and the movable contact 13 will set them with respect to the contacts on the arm 10 for the desired amount of tolerance. The contacts 12 and 13 are grounded through their supporting arms 14 and 114. The contacts on the metallic insert 104 of arm 10 are wired to an electronic switch.

Referring to the electrical diagram, the operation will be described with reference to the left hand gauge and the corresponding parts controlled by it. The right hand gauge operates in the same way but a half cycle later. The cycling timer and the two electronic switches S and S1 in the diagram are commercial items and are wired to alternating current mains A and B. The cycling timer has a relay whose contacts open and close at a rapid rate. The armature of this relay is connected to ground so that lines C and D are successively grounded as the armature oscillates between these two lines. Line C is connected to one side of solenoid 24, the other side being connected to main B. Thus, solenoid 24 is energized and deenergized at a rapid rate which is predetermined by the setting of the controls on the cycling timer.

The electronic switches are electronic devices which cause an internal relay to close if and when a control wire, such as lines J or P, becomes grounded by one of the gauges. The current flowing through this control wire can be very minute, say a few microamperes, and therefore there will be no arcing when this control wire touches a grounded object to complete its circuit. This property lends itself to gauging, since even a very minute separation (less than .0001") is sufficient to break this circuit. Thus, since lines J and P are connected to the metallic inserts of their respective gauges, one of these lines will become grounded whenever an oversize or undersize roller causes the insert to engage either of the grounded contacts 12 or 13, thereby effecting closure of the relay contacts in the corresponding electronic switch.

Assume now that only rollers within acceptable limits are passing through gage No. 1. The relay of electronic switch S is then in the open position as it is set to be for acceptable rollers, thus making it impossible for relay A3 to operate. Assume also the very short instant that the cycling timer is in the position for grounding line D. Line C is therefore not grounded so that solenoid 24, relays A1 and A2 and the left hand solenoid 20 will all be unenergized. During the next half cycle when the acceptable roller is to be ejected, line C becomes grounded and a circuit is completed from line C, through the normally closed contacts of relay A3, line E, the normally closed contacts of relay A1, line F, the coil of relay A2 and finally to line B. Relay A2 therefore will be energized and the contacts between lines K and H will be opened. This is necessary since solenoid 24 is also energized at this instant and the transfer of the roller be-

ing gaged out of the gaging position disturbs the position of the gaging contacts and might otherwise cause closure of the contacts in the electronic switch S. Hence the opening of the normally closed contacts of relay A2 during ejection of rollers from the gage prevents gaging errors from being transmitted to relay A3 which controls the opening of the trap door solenoid 20 which opens only for unacceptable rollers. So, as long as only acceptable rollers pass through gage No. 1, only relay A2 will be energized simultaneously with solenoid 24 while relays A3 and A1 and solenoid 20 will remain unenergized and no trap door will open.

Next, assume that an off-limit roller, undersize or oversize, has been presented to gage No. 1. The insulating gauge arm 10 will then move the metallic insert 104 into contact with either the contact 12 or the contact 13 both of which are grounded and, since insert 104 is connected to line J, a circuit will be completed through the electronic switch S. The relay contacts in the electronic switch will then close as they are set to do for off-limit rollers but this will not immediately affect the rest of the circuit since relay A2 remains energized for the short interval that line C remains grounded. As the contacts in the cycling timer relay transfer the ground circuit from line C to line D, solenoid 24 and relay A2 will be deenergized. When the off-limit roller has thus caused the relay contacts of the electronic switch to connect line A to line K, a circuit is completed through line H and the coil of relay A3 to main line B. Energizing of relay A3 connects line C to line G and, when line C is grounded on the next half cycle, the trap door solenoid 20 is energized simultaneously with the solenoid 24 which ejects the roller. At the same time, relay A1 is energized and a holding circuit therefor is completed through lines M and N and the lower of the two contacts thereby transferring control of relay A1 and solenoid 20 directly to the contacts of the cycling timer independently of relay A3.

The upper contact of relay A1 opens the coil circuit of relay A2 to prevent it from being energized during this half cycle of the timer. Both contacts are used to prevent relay A1 and the solenoid 20 from being deenergized and to prevent relay A2 from being energized during transfer of the off-limit roller out of the gaging position, especially since the following roller may be O. K., whereupon the contacts of the electronic switch S would open.

During the following half-cycle of the timer, the circuit from the ground to line C will be broken and solenoids 24 and 20 as well as relay A1 will be deenergized. Relay A3 will remain energized through the electronic switch if an off-limit roller is between the gage contacts or will be deenergized if the roller is O. K.

The circuit for gage No. 2 is similarly connected to the mains and to the cycling timer and acts the same as for gage No. 1 except that operation of the relays and solenoids will occur during the following half-cycle of the timer which grounds the lines C and D in rapid succession.

Summarizing the timing of important events many of which occur simultaneously and starting with the relay of the electronic switch S open, as it is set to be for acceptable rollers, and with line C about to be grounded by the cycling timer:

1. Line C is grounded. Solenoid 24 and relay A2 are energized. If gauged roller is of accept-

able length no door opens and the roller is ejected over it.

1A. If the roller is off limits. Gauge arm 10 engages contact 12 or 13 energizing electronic switch S and closing its relay.

2. Line D is next grounded to disconnect line C, deenergizing solenoid 24 and the relay A2, lines K and H thereby being connected and relay A3 being energized to connect C to line G.

10 3. Line C is next grounded, solenoids 24 and 20 thereby being energized along with relay A1 while relay A2 is deenergized. The door opens and the roller passes under it.

4. Line C is next broken. Solenoids 24 and 20 and relay A1 are deenergized.

15 5. Relay A3 remains energized through the electronic switch if the next roller is off limits but it is deenergized if the next roller is of acceptable length because the relay of S opens.

20 I claim:

1. In a gauging machine, a work supporting platform, a stop surface rising therefrom, means for directing elongated articles endwise in successive engagement with the platform and into end contact with the stop surface, a movable door at the side of the platform, a gauging finger movable towards or from the stop surface in accordance with the length of an article therebetween, gauging finger controlled mechanism to select the position of the door, a transfer member movable laterally over the platform to laterally push a first article between the stop surface and the gauging finger, and means for oscillating the transfer member to cause a subsequent article to engage the first and discharge it at the selected side of the door.

2. In a gauging machine, a work supporting platform, a stop surface rising therefrom, a movable door opening against the side of the platform, a gauging finger movable towards and from the stop surface in accordance with the length of an article end-engaged therebetween, gauging finger regulated mechanism to select the position of the door, and means for moving articles laterally between the stop surface and the gauging finger to discharged positions on selected sides of the door.

3. In a gauging machine, a work supporting platform, a stop surface rising therefrom, a gauging finger movable towards or from the stop surface in accordance with the length of an article therebetween, a yieldable locating finger overlying the platform to line up each article for gauging, a transfer member overlying the platform, and mechanism laterally oscillating the transfer member to push articles laterally against the locating finger and thereafter discharge the articles in the same lateral direction beneath and past the locating finger and into a selected path determined by the gauging finger.

4. In a gauging machine, a work supporting platform, a stop surface rising therefrom, means for directing articles endwise over the platform into contact with the stop surface, a gauging finger and a locating finger near one side of the platform, a transfer member extending downwardly and closely overlying the platform in front of the stop surface, means for oscillating the transfer member to push articles laterally against the locating finger, and adjustable mechanism for limiting the movement of the transfer member in the direction of the locating finger.

5. In a gauging machine, a work supporting platform, a stop surface rising therefrom, means

for directing articles endwise in succession against the platform into end contact with the stop surface, a gauging finger at each side of the platform, each gauging finger being movable towards or from the stop surface into engagement with another end of said article in accordance with the length of the article therebetween, a transfer member overlying the platform between the gauging fingers and movable across the path of articles approaching the stop surface, means for laterally oscillating the transfer member to push articles laterally to the gauging fingers in succession, and means for causing successive lateral movements of the transfer member in a given direction to push a subsequent article against a gauged article to discharge the latter in a path selected by its gauging finger.

6. In a gauging machine, a work supporting platform, a movable gauging finger above and near each side of the platform and spaced from and in opposed relation to a fixed gauging surface, a movable door at each side of the platform, a laterally oscillatable member for pushing articles laterally in each direction from a central position on the platform to a gauging position and laterally beyond, and means controlled by each gauging finger for moving the adjacent door to deflect an article when an article of a specified dimension passes the gauging position.

7. In a gauging machine, a cycling timer, an electronic switch connected to the timer and having a relay set to close when gauged articles are of unacceptable dimensions, a gauging device controlling the electronic switch and controlling the relay, means for presenting articles to the gauging device, a door, a transfer member for discharging articles from the gauging device to the door, and a circuit controlled by the relay to operate the door and separate articles of unacceptable dimensions from the others.

8. In a gauging machine, a work supporting platform, a gauging lever of insulating material projecting over the platform to measure an article thereon, electric contacts carried by the lever, an electronic switch connected to the lever contacts, grounded contacts spaced from the lever contacts when an article measured by the gauging lever is of acceptable dimensions, an article deflecting door at one side of the platform and normally urged towards the platform, a solenoid connected to the door, a circuit controlled by the electronic switch when one of the lever contacts engages one of the grounded contacts to operate the solenoid and retract the door, and means for discharging the measured article in the path selected by the door.

9. In a gauging machine, means for moving articles to a movable gauging position, a gauging lever of insulating material having a pair of electric contacts, an electronic switch connected to said contacts, grounded contacts arranged to be engaged by the lever contacts when articles are of unacceptable size, means for discharging articles from gauging position, and a circuit controlled by the electronic switch when one of the lever contacts engages one of the grounded contacts to determine the path of article discharge.

10. In a gauging machine, a work supporting

platform, a stop surface rising therefrom, mechanism for directing elongated articles endwise in successive engagement with the platform and into end contact with the stop surface, a movable door at the side of the platform, a gauging finger movable towards and from the stop surface in accordance with the length of the article therebetween, gauging finger controlled mechanism to select the position of the door, a movable transfer member overlying the platform, and mechanism for laterally oscillating the transfer member to position articles laterally in end engagement with said stop surface and into end engagement with the gauging member and to discharge them at the side of the door selected by the movable gauging finger.

11. In a gauging machine, a work supporting platform, a stop surface rising therefrom, means for directing articles endwise in successive sliding engagement with the platform and into end contact with the stop surface, a locating finger near one side of the platform, a door movable towards and from the side of the platform, a movable gauging finger in spaced relation to the stop surface engageable with an end of one of said articles to gauge its length while it is located on the platform, gauging finger responsive mechanism controlling the position of the door, a laterally oscillatable transfer member overlying the platform, mechanism for moving the transfer member to push a first article laterally against said locating finger to line up the article in end engagement with the stop surface and with the gauging finger, and mechanism causing the transfer member to move a subsequent article against the gauged article to discharge the gauged article on a selected side of said door.

12. In a gauging machine, a work supporting platform, a stop surface rising therefrom, mechanism for directing elongated articles endwise in succession along the platform into end contact with the stop surface, a gauging finger engageable with the opposite end of the article from that engaging said stop surface and movable towards and from the stop surface in accordance with the length of the article being gauged, a transfer member overlying the platform and laterally movable across the path of the articles approaching the stop surface, and mechanism laterally oscillating the transfer member to push articles laterally into a longitudinal position between the stop surface and the gauging finger.
